UNITED STATES PATENT OFFICE.

ALONZO LINTON BAUSMAN, OF CHICOPEE, MASSACHUSETTS, ASSIGNOR TO NATIONAL EQUIPMENT COMPANY, OF SPRINGFIELD, MASSACHUSETTS, A CORPORATION OF MASSACHUSETTS.

PLAQUE-CLEANING MACHINE.

1,275,365.

Specification of Letters Patent. Patented Aug. 13, 1918.

Application filed September 12, 1917. Serial No. 190,911.

To all whom it may concern:

Be it known that I, ALONZO LINTON BAUSMAN, a citizen of the United States of America, residing at Chicopee, in the county 5 of Hampden and State of Massachusetts, have invented certain new and useful Improvements in Plaque-Cleaning Machines, of which the following is a specification.

This invention relates to improvements 10 in machines for cleaning plaques and the like. My prior Patent No. 928,730, dated July 20, 1909, illustrates the prior art in machines of this character.

In confectionery manufacture, it is customary to employ strips of waxed paper, 15 technically known as plaques, on which confections are placed after they have been coated and usually while the coating is still soft. In removing the coated confections 20 from the plaques, particles of the coating material sometimes adhere to the waxed surface, and, after an accumulation of such particles, the plaques require cleaning. Heretofore, plaques have been cleaned by brushing 25 or by beating with rotatable spring fingers. A disadvantage, in the prior methods of removing the particles of coating material from the plaques lies in the fact that the very agents employed to loosen the 30 particles may act to work the latter into the waxed coating with the result that the plaques, although apparently clean, are not clean in fact. Furthermore, a brushing action, in order to be effective in loosening 35 and removing the particles, must bear with relatively large pressure on the plaques and thus such action tends to wear and injure the wax coating of the plaques, rendering the life of the latter relatively short.

According to one feature of the invention, 40 the particles adhering to the plaques are first loosened by a plowing action with relatively small pressure on the plaques, and the loosened particles are subsequently removed 45 by lightly brushing them from the plaques, the arrangement being characterized in that the particles are effectively removed without injuring the waxed coating of the plaques and without tending to rub the particles 50 into the waxed surface.

According to another feature of the invention, the relatively large lumps of coating material on the plaques are first subdivided into smaller particles by a light plowing action, and such particles as are loosened

by this action are subsequently lightly brushed from the plaques before the final plowing and brushing operations.

According to another feature of the invention, the final plowing action to loosen 60 the relatively small particles is accomplished by plowing members, which approach the particles from different angles and substantially opposite directions for the purpose of more effectively loosening the 65 particles and insuring that such of the latter as may adhere to the plaques after the operation of one member will be subsequently loosened by the operation of another member. 70

According to a further feature of the invention, the plowing and brushing actions are directed substantially at right angles to the direction of travel of the plaques, and the loosened particles are brushed laterally 75 from the plaques into suitable receptacles.

Other features of the invention will appear in the following description and in the illustrative embodiment of the invention in the accompanying drawings, in which— 80

Figure 1 is a plan view of the machine;
Fig. 2 is an elevational view of the left end of Fig. 1;

Fig. 3 is a sectional elevational view taken on the line 3—3 of Fig. 2; 85

Fig. 4 is a perspective view of a fragment of the conveying belt showing the plaque holding flaps thereon;

Figs. 5 and 6 are detail cross sectional views taken on the lines 5—5 and 6—6, respectively, of Fig. 1; and 90

Fig. 7 is a fragmentary sectional elevation of a portion of the cleaning mechanism.

Referring to these drawings, reference letter A indicates the main frame of the machine and rotatably mounted in opposite ends of frame A are rolls 10 and 11 (Fig. 2), over which runs an endless belt 12 of suitable material, as canvas, for example. Roll 11 is mounted for adjustment longitudinally in a manner clearly shown in Fig. 2, and by moving screws 13 the tension of belt 12 may be varied as desired. The belt is driven from roll 10 to which is fixed a gear 14, and the latter is engaged by a pinion 15 to which is fixed a gear 16. The latter is driven by a pinion 17 on the main drive shaft 18 of the machine, as shown in Fig. 1. The upper travel of belt 12 is substantially horizontal and the belt in its upper 105

travel moves with its under face contiguous with and supported by a table 19 carried by frames A.

The belt 12 is provided at suitably spaced intervals with flaps 20 which are suitably secured thereto, as by stitching along one edge. The plaques, indicated by reference letter *p*, are simply paper strips coated with wax or the like. As indicated in Fig. 4, the plaques *p* are held to the conveyer belt 12 by inserting the leading end of each plaque in under a flap 20. The flaps are so constructed that they will of themselves frictionally hold the plaques in position on belt 12 during the upper travel of the latter. During the lower travel of the belt and as the latter travels around the rolls 10 and 11, the flaps 20 may open to some extent as indicated in Fig. 2.

With the illustrated embodiment of the invention, the plaques to be cleaned are inserted in under flaps 20 by an operator who stands at the right hand end of the machine (Fig. 2), and the plaques are arranged to travel to the left hand end of the machine and to the under side of roll 10, wherefrom they may drop into a suitable receptacle not shown.

A curved guide plate 21, supported from frame A in concentrical relation with roll 10 and closely adjacent the periphery thereof, is arranged to hold the flaps 20 closed as they travel between the guide 21 and roll and to hold the free end of the plaques from falling until they have been carried to the desired point. As the flaps 20 start to travel on the upper periphery of roll 10, the flaps may open up to an extent sufficient to release their frictional grip on the plaques *p*.

To insure that the latter are carried with the belt at this point, irrespective of whether or not the flaps open up in the manner described, a roll 23 (Fig. 1) is mounted in spring pressed bearings 24 (Fig. 2) so that it yieldingly forces the plaques *p* against the conveyer belt. Roll 23 is driven by a pinion 25 which meshes with the described gear 14. The driving connections are such that roll 23 is driven at the same surface speed as belt 12, whereby the plaques are carried with the belt as the latter travels around roll 10, and the grip of the flaps need not be relied upon to hold the plaques to the belt during this portion of their travel.

It is to be noted that the leading ends of the plaques *p*, those inserted under flaps 20, are ordinarily free from chocolate and the like because they are usually held by like flaps when used in the ordinary commercial automatic coating machine to receive the coated goods and therefore require no cleaning. It is also to be noted that roll 23 is so located as to engage the plaques only after the latter have been cleaned by the means to be described.

The mechanism for cleaning the plaques comprises reciprocatory members 30, 31, and 32, and brushes 33 and 34, all mounted to travel transversely relatively to the conveying belt 12. The members 30, 31, and 32 are mounted to slide longitudinally and vertically in suitable guides 35, and, as shown in Fig. 2, are yieldably forced against the plaques on belt 12 by springs 36, the tension of which is adjustable by thumb screws 37. Each member 30, 31, and 32 is pivotally connected near its central portion to one end of a rod 38 (see Fig. 3) and on the other end of the latter is an eccentric strap 39 which embraces an eccentric 40, fixed on a shaft 41, supported in longitudinal relation on frame A. The eccentrics 40 for members 31 and 32 are preferably arranged in opposition, as indicated in Fig. 1.

The brushes 33 and 34 are each mounted on an endless band 42 which is carried by pulleys 43 and 44, the former being fixed to shaft 41 and the latter being loosely mounted on a stud 45. Each stud, as shown in Fig. 3, is adjustably mounted in a bracket 90 secured to frame A, and, by moving the stud, the tension of band 42 may be adjusted as desired. An idler pulley 46, adjustably mounted in a bracket secured to frame A, as shown in Fig. 3, directs the lower travel of belt 42 in parallel relation with the table 19. The shaft 41 is connected by a gear train 48, as best shown in Fig. 3, to a shaft 49, and the latter is connected by bevel gears 50 (Figs. 2 and 3) to the described main drive shaft 100 18. Preferably, receptacles 54 are removably secured to frame A, as indicated in Fig. 7, and belts 42 are arranged to travel through the receptacles to deposit therein the particles swept from plaques *p* by the brushes. 105

Secured to the under face of member 30 and arranged in longitudinally spaced parallel relation thereon are a plurality of substantially U-shaped wires 51, and the cross bar portion of the U, which is bent in corrugated or undulatory form, is arranged to engage the plaques *p*. The wires 51, as shown in Fig. 1, are slightly inclined to the direction of travel of belt 12 and, preferably, the inclination adopted is such that one end of each corrugated portion of the wires 51 is disposed substantially opposite on member 30 from the opposite end of the corrugated portion of the next succeeding wire. In this way, a plowing rather than a scraping action results, and it is insured that all portions of the plaque will be engaged by the wires. 120

The member 31 has similarly mounted and similarly spaced U-shaped wires 52 and, as shown in Fig. 5, the cross bar portions of the U are straight and parallel to the member 31. Wires 52 are also inclined to the direction of travel of belt 12 but preferably are inclined oppositely to the wires 51, as 130

shown in Fig. 1. The member 32 is also provided with U-shaped wires 53 which are identical in form with the wires 52, shown in Fig. 5. Wires 53, as shown in Fig. 1, are 5 inclined to the direction of travel of belt 12 and preferably oppositely inclined to wires 52. Both sets of wires 52 and 53 are preferably inclined, as described in connection with the wires 51, so that an end of each lies 10 substantially opposite the opposite end of the next succeeding wire.

In operation, the plaques are inserted under flaps 20, as described, and thereby caused to travel with the belt. The sets of reciprocable wires and the traveling brushes are arranged to bear but lightly on the plaques *p* and do not exert sufficient force on the latter to overcome the frictional engagement of the plaques with the flaps 20 or with belt 20 12. The plaques first travel in under the set of wires 51 and these wires are being reciprocated at a speed somewhat higher than that of the conveyer. The large number of corrugated wires 51 are thus moved back and 25 forth on the plaque and plow through the relatively large deposits or lumps of chocolate or other like material. The purpose of the corrugated wires is to break up and subdivide the larger deposits so that they may 30 be removed more readily by the other portions of the cleaning mechanism. The wires 51 will, however, break off and loosen a certain amount of the material from the plaques and such loosened portions are subsequently 35 removed by the continuously traveling brushes 34, which lightly brush across the plaques without exerting much pressure thereon. The plaques next come in under the reciprocable sets of wires 52 and 53 40 which act to loosen any small portions of material from the plaques by a plowing action. The sets of wires 52 and 53 always plow from opposite directions and this in connection with the opposite inclination of 45 the two sets insures that such portions as are not loosened by one set will undoubtedly be loosened by the next set when approached in a different direction and at a different angle. The particles loosened by 50 the sets of wires 52 and 53 are then carried laterally from the plaques by the continuously traveling brush 34. The cleaned plaques *p* then pass under roll 23 for the purpose described and are subsequently carried partially around roll 10 55 and allowed to drop into a suitable receptacle. The particles of material removed from the plaques are carried by the brushes 33 and 34 into the receptacles 54 from which 60 they may be removed from time to time as desired.

A most important feature of the invention consists in the arrangement, whereby the material adhering to the plaques is first 65 loosened by a light plowing action and sub-

sequently removed by lightly brushing the loosened particles laterally from the plaques. The several members acting on the plaques are arranged to exert only a very small amount of pressure thereon with the 70 idea of preventing injury to the waxed surface. The illustrated arrangement avoids the possibility of beating the particles into the wax coating and avoids undue wear on the latter. As distinguished from beating, 75 scraping, or violent brushing actions, the removal of the particles is accomplished rather by a preliminary gentle plowing action for the purpose of sub-dividing the particles into particles of lesser size and a 80 final and likewise light plowing action on the remaining unloosened particles and lightly brushing the loosened particles from the plaques after both the preliminary and final plowing actions. The traveling 85 brushes are not capable of both loosening and removing the particles unless they bear with considerable pressure on the plaques. Such pressure is undesirable as being injurious to the wax coating, but by combining a light plowing action with a light brushing action, neither of which can cause injury to the wax coating of the plaques, the latter may be most effectively cleaned. 90 The entire apparatus is also characterized 95 by the elimination of rolls or equivalent devices which can act on the unclean portions of the plaque with a tendency to rub or force particles of chocolate or confectionery material into the waxed surface of the 100 plaques.

The invention has been disclosed, in an embodiment at present preferred, for illustrative purposes, but the scope of the invention is defined by the appended claims 105 rather than by the foregoing description.

What I claim is—

1. In a machine of the class described, a conveying means for plaques or the like and means laterally movable with relation to the conveying means to engage particles on said plaques obliquely to the direction of travel of the conveying means, and loosen the particles from the plaques.

2. In a machine of the class described, a conveying means for plaques or the like, means laterally movable with relation to the conveying means to engage particles on said plaques obliquely to the direction of travel of the conveying means and loosen the particles from the plaques, and means to lightly brush the loosened particles from the latter.

3. In a machine of the character described, a conveying means for plaques or the like, means to lightly engage the surface of the latter and subdivide relatively large particles of material adhering thereto, and means subsequently operable to loosen the subdivided particles.

4. In a machine of the character described, a conveying means for plaques or the like, means to lightly engage the surface of the latter and subdivide relatively 5 large particles of material adhering thereto, means subsequently operable to loosen the subdivided particles, and means to lightly brush the loosened particles from said plaques.
- 10 5. In a machine of the character described, a conveying means for plaques and the like, plowing means lightly engageable with the surface of the latter to break up relatively large particles adhering to said 15 surface, means to lightly brush particles loosened by the last-named means from the plaques, another plowing means to loosen remaining particles adhering to said surface, and means to lightly brush the particles loosened by the last-named means from 20 said plaques.
6. In a machine of the class described, a conveying means for plaques or the like, a member reciprocable across said means, and 25 a plurality of substantially U-shaped devices carried by said member to engage the plaques, the plaque engaging portion of said devices being arranged obliquely to the direction of travel of said conveying means, 30 whereby particles adhering to the plaques may be loosened by said devices.
7. In a machine of the class described, a conveying means for plaques or the like, a member reciprocable across said means, a 35 plurality of substantially U-shaped devices carried by said member to engage the plaques, the plaque engaging portion of said devices being arranged obliquely to the direction of travel of said conveying 40 means, whereby particles adhering to the plaques may be loosened by said devices, and brushing means movable laterally across the conveying means, whereby particles loosened by said devices may be removed from the plaques.
8. In a machine of the class described, a conveying means for plaques or the like, a set of substantially U-shaped members reciprocable laterally of said means and 50 adapted to engage the plaques, each of said members having their plaque engaging portions disposed obliquely to the directions of travel of said conveying means, a second set of substantially U-shaped members recipro- 55 ciprocable laterally of the conveying means and movable in a direction opposite to the first-named set, each of the members of the last-named set having their plaque engaging portions arranged at an angle to the 60 direction of travel of the conveying means and being inclined oppositely to the members of the first-named set.
9. In a machine of the class described, a conveying means for plaques or the like, a 65 member reciprocable laterally of said means, a set of substantially U-shaped devices carried by said member and adapted to engage said plaques, the plaque engaging portion of said devices being of corrugated shape, and constructed to break up and subdivide 70 relatively large deposits or lumps of material adhering to said plaques, and means to subsequently loosen the deposits subdivided by said devices.
10. In a machine of the class described, 75 a conveying means for plaques or the like, means to loosen particles of material adhering to the plaques, and a traveling brush movable across the conveying means to lightly engage the plaques and sweep the 80 loosened particles therefrom.
11. In a machine of the class described, a conveying means for plaques or the like, means to loosen particles of material adhering to the plaques, and a traveling brush 85 continuously movable across the conveying means in one direction to lightly sweep the loosened particles from said plaques, and a receptacle arranged to receive such particles, whereby the particles swept from 90 the plaques may be deposited in said receptacle.
12. In a machine of the class described, 95 a conveying means for plaques or the like, means to loosen particles of material adhering to the plaques, and a traveling brush continuously movable across the conveying means in one direction to lightly sweep the loosened particles from said plaques, and a receptacle through which said brush is 100 arranged to travel, whereby the particles swept from the plaques may be deposited in said receptacle.
13. In a machine of the class described, 105 a conveying means for plaques or the like, a member reciprocable adjacent and substantially at right angles to the direction of travel of said conveying means, a plurality of substantially U-shaped wires mounted on said member in spaced parallel 110 relation, and means to yieldingly force said member toward the conveying means, whereby the cross bar portion of said wires may lightly engage the plaques on said means, the cross bar portions of said wires 115 being inclined to the direction of travel of the conveying means.
14. In a machine of the class described, 120 a conveying means for plaques or the like, a member reciprocable adjacent and substantially at right angles to the direction of travel of said conveying means, a plurality of substantially U-shaped wires mounted on said member in spaced parallel relation, and means to yieldingly force said member toward the conveying means, whereby the cross bar portion of said wires may lightly engage the plaques on said means, the cross bar portions of said wires being inclined to 125 the direction of travel of the conveying 130 means.

means, and so inclined and so spaced that an end of each lies substantially opposite on said member from the opposite end of the next adjacent cross bar portion.

5 15. In a machine of the character described, a conveying means for plaques or the like, two members reciprocable in opposition adjacent said means and in a direction substantially at right angles to that 10 of the conveying means, a plurality of substantially U-shaped wires mounted in closely spaced parallel relation on each member, means to lightly and yieldingly force each member toward the conveying means so that 15 the cross bar portions of said wires will engage the plaques on the latter, the said portions on each member being inclined to the direction of travel of the conveying means, and said portions on one member being oppositely inclined to those on the other 20 member.

16. In a machine of the character described, a conveyer for plaques or the like, plowing means reciprocable laterally of said 25 means and arranged to engage the plaques on the latter to loosen deposits of material thereon, and means to remove the loosened deposits comprising a brush carrying endless band mounted to travel across and 30 above the conveying means and so that in its lower travel the band moves parallel with the last-named means.

17. In a machine of the class described, a conveyer for plaques or the like, a device 35 reciprocable laterally of the conveyer to engage the plaques thereon and loosen and subdivide relatively large deposits of mate-

rial on the latter, a brush continuously traveling across the conveyer to sweep the deposits loosened by said devices from the 40 plaques, plowing devices reciprocable laterally of the conveyer to subsequently engage the plaques and loosen the subdivided deposits thereon, a brush continuously traveling across the conveyer to sweep the loosened deposits therefrom, a common operating 45 shaft for all said brushes and devices, means on the shaft to drive said brushes continuously in one direction, eccentrics on the shaft, and connections between the latter 50 and said devices to reciprocate the latter, the eccentrics for said plowing devices being arranged so that successive devices move in opposite directions.

18. In a machine of the class described, a 55 conveyer for plaques or the like, a device reciprocable laterally of the conveyer to engage the plaques thereon and loosen and subdivide relatively large deposits of material on the latter, a brush continuously traveling across the conveyers to sweep the deposits loosened by said devices from the 60 plaques, plowing devices reciprocable laterally of the conveyer to subsequently engage the plaques and loosen the subdivided deposits thereon, a brush continuously traveling across the conveyer to sweep the loosened deposits therefrom, a common operating 65 shaft to drive said brushes and reciprocate said devices, and a driving means 70 for the shaft and conveyer arranged to drive the former at a higher speed than the latter.

ALONZO LINTON BAUSMAN.
